COMBINATION TIPPING AND SILL HOOK

George Le Roux, Nashua, N. H.

Application August 5, 1933, Serial No. 683,724

4 Claims. (Cl. 294—82)

This invention relates to such hooks as are used for lifting heavy weights. It is particularly useful in lifting derailed railroad cars which block traffic on railroads where speed is essential.

5 In clearing tracks of such cars, it is usually desirable to use a lifting device from which extends a hanger such as a wire rope on the end of which is a hook and to hook such a hook or several hooks under whatever part of the car happens to be at the bottom and to then raise that edge until the whole car topples over in the opposite direction.

Usually such cars when derailed are right side up, but this device will apply in any case where it 15 is possible to get the tip end of a hook underneath. Under ordinary circumstances there may be a small metal flange along the bottom outside edge of the railroad car and the side extends up at ninety degrees from the bottom. Under such 20 circumstances, the point of this hook which is preferably of hardened metal of some sort can be brought up underneath and inside such a flange while a shank in extension of the body of the hook medially pivoted on an arm attached to the hanger rests against the side of the car.

When the whole outfit is lifted, the downward pressure on the hook point, which is in advance of the pivot, causes the shank to follow the side of the car until the center of gravity of the car 30 passes beyond a perpendicular line extending up from the edge on which the car is resting, whereupon the car continues to tip, automatically releasing itself from the hook and its shank which is moving around on the pivot with the car up 35 to that time, and to fall over.

However, in the preferred construction, by inserting a pin through lock pin holes, the hook can be used as an ordinary lifting hook without the automatic releasing feature.

40 By extending a shank upwardly beyond the pivot and on the opposite side from the claw member of the hook, the hook is prevented from slipping out and releasing the load to be lifted before the load is tipped beyond the center of gravity so that it will fall over. The presence of this shank extension causes the hook to cling to the bottom of a load, such as a car, near the edge until the tipping point is reached, upon which the load releases itself from the hook and, as it moves 45 at that point in the same direction as the hardened point of the hook, it clears itself from that point in case the point has imbedded itself in the wood.

In the drawing, Fig. 1 is a side elevation of the 55 hook, with the lock pin removed, engaged under

one edge of an object such as a car body which is to be tipped over.

Fig. 2 is a view similar to Fig. 1 showing the position of the parts when the hook has been raised sufficiently so that the load is releasing itself.

Fig. 3 is a diagrammatic cross sectional view showing a box or car body or similar load resting on the ground in full lines and in dotted lines showing the various positions as the hook is 10 lifted. The first dotted position shows the load releasing itself and the second dotted position shows the load tipped entirely over.

Fig. 4 is a view similar to Fig. 1 of the hook with the lock pin in place.

Fig. 5 is a horizontal sectional view looking down on line 5—5 of Fig. 1 and Fig. 6 on line 6—6.

In the drawing, L represents a load such as a derailed car which is to be tipped over so as to remove it from the tracks. 12 represents a side 20 which is perpendicular to the floor or bottom 10, 11 representing the edge between them and 13 representing an angle iron such as is frequently found as a part of such cars.

H represents a hanger shown as a cable at the 25 end of which is a metal pivot holder 20 for a pivot such as 22.

A is an arm hung at one end on pivot 22 and having at its other end a hook pivot 23 and through its shank 21 the lock pin hole 24.

C represents a hook medially pivoted on pivot 23 at 33 and having a shank 31 which extends beyond the pivot point 33 in a direction opposite from the claw part 37. Said shank has the wings 30 through which are lock pin holes 34, 34 35 adapted to register with the lock pin hole 24 in the arm A and to be locked in place therewith by a lock pin P. The front 35 of this shank when so locked is so made as to be substantially parallel with the vertical hanger such as H and 20 and 40 the claw member 37 extends down from the pivot and thence curves around at 38 to a hardened metal point 39 which will be in front of the face 35 of shank 31 when the parts are locked together and will also be in front of such shank 45 when, as shown in Fig. 1, lock pin P is removed, but the part 35 rests against the side 12 of car L.

The hook pivot 23 is so located and the weight of the claw member 37 at 38 and 39 is so distributed that when the hanger H suspends the 50 arm A and the hook C, the shank 31 is maintained by gravity in a substantially vertical position.

The claw of the hook can, therefore, be swung on its rope so that the point will go under the 55

edge of the load and when lifted, it will bite in and hang on to the load with the shank resting against the side of the load and following it along until the load passes beyond its center of gravity 5 and releases itself from the hook, all without the human hand touching any part of the hook.

With lock pin P in place in holes 34, 34 and 24, as shown in Fig. 4, the device can be used as an ordinary lifting hook which will not release its 10 load, but with pin P removed, it will act as shown in Fig. 3.

A car L is derailed and resting with its floor 10 and one bottom edge 12 on the ground T. Hook C is brought under edge 11 and iron 13 with front 15 face 35 of shank 31 resting against side 12. As hook A is lifted by hanger H, shank 31 follows 12 as shown in the dotted lines until the center of gravity of L passes over pivot edge 12 when edge 11 will release itself and iron 13 from hook A and 20 the car L will topple over.

I claim:

1. In a wrecking device, the combination of a vertical hanger; with an arm pivotally hung at one end thereto, said arm having a hook pivot at 25 its other end and a lock pin hole between the ends; a hook medially pivoted to the bottom of the arm and having a shank which extends upwardly in front of said arm, said shank having wings with lock pin holes adapted to register with 30 the lock pin hole in the arm, the front of the shank being substantially parallel with the vertical hanger, and a claw member extending down from the pivot and up to a hardened metal point in front of the face of the shank; and a 35 lock pin which passes through the pin holes in the wing and the shank.

2. In a wrecking device, the combination of a

vertical arm having a hook pivot and a lock pin hole; with a hook medially pivoted to the bottom of the arm and having a shank which extends upwardly in front of said arm, said shank having wings with lock pin holes adapted to register with the lock pin hole in the arm, the front of the shank being substantially parallel with the vertical hanger, and a claw member extending down from the pivot and up to a hardened metal point in front of the face of the shank; and a 5 lock pin which passes through the pin holes in the wing and the shank.

3. In a wrecking device, the combination of a vertical hanger; with an arm pivotally hung at one end thereto, said arm having a hook pivot at 15 its other end; a hook medially pivoted to the bottom of the arm and having a shank which normally extends upwardly in front of said arm, the front of the shank being substantially parallel with the vertical hanger, and a claw 20 member extending down from the pivot and up to a hardened metal point in front of the face of the shank; and means for securing the shank of the hook to the arm when the hook is in load supporting position.

4. In a wrecking device, the combination of a vertical arm having a hook pivot; with a hook medially pivoted to the bottom of the arm and having a shank which normally extends upwardly in front of said arm, the front of the shank being substantially parallel with the vertical arm, and a claw member extending down from the pivot and up to a point in front of the face of the shank; and means for securing the shank of the hook to the arm when the hook is 30 in load supporting position.

GEORGE LE ROUX.
